OIL BURNER INSTALLATION

William A. Purtell, West Hartford, Conn., assignor
or to The Sparmal Engineering Corporation, a
corporation of Connecticut

Application March 9, 1939, Serial No. 260,772

8 Claims. (Cl. 122—494)

My invention relates to oil burners.

It has among its objects to provide an improved oil burning unit. A further object of my invention is to provide such an improved unit of an improved construction especially adapted to use in connection with a boiler and having the latter forming a part thereof. Another object is to provide improved means including an improved casing and an improved heating unit for enabling the oil burner and its associated mechanism to be readily inserted in and removed from operative position beneath such a boiler. Still another object is to provide improved combustion chamber forming means including an improved slide for the oil burner and having improved air circulating and insulating structure and also having on said slide a removable closure including improved cooperating air circulating and insulating means in said combustion chamber. Other objects include the provision of an improved arrangement of the burner and control mechanism on this slide and relative to such a combustion chamber closure thereon, and improved supply connections also connected to said slide, all whereby the slide may be readily withdrawn as a unit from operative position in the combustion chamber when desired to permit ready servicing or substitution of another unit as necessary. These and other objects and advantages of my improvement will, however, hereinafter more fully appear.

In the accompanying drawings, I have shown for purposes of illustration one embodiment which my invention may assume in practice.

In these drawings—

Figure 1 is a perspective view of my improved unit, the slide carrying the burner mechanism being shown in withdrawn position and the boiler being broken away to facilitate illustration;

Fig. 2 is a central vertical section through the unit, the upper portion of the boiler being omitted to facilitate illustration, and certain parts on the slide mechanism being shown in elevation;

Fig. 3 is a view similar to Figure 2, but showing the slide withdrawn and the parts thereon in side elevation;

Fig. 4 is a sectional view on line 4—4 of Figure 3, and

Fig. 5 is a sectional view on line 5—5 of Figure 3.

In this illustrative construction, I have shown my improved unit as including a vertical boiler 1 and having a horizontally disposed burner casing 2 beneath the same, this casing 2 having therein reciprocable slide mechanism, generally

indicated at 3, carrying thereon an oil burner and its controlling mechanism and supply connections, and this slide mechanism being adapted to be inserted in operative position in the casing 5 2, as shown in Figure 2, or withdrawn, as shown in Figure 1, all in an improved manner and as hereinafter more fully described.

Referring more particularly to the boiler 1, it will be noted that the same is a vertical boiler 10 and mounted on the top and at the rear of the casing 2. As shown, a suitable aperture 4 is provided in the top of the casing 2 adapted to receive the lower end of the boiler unit and support the outer shell thereof, while the tube carrying structure 5 of the boiler is carried on suitable inner supports 6 in the top of the casing 2. Passage means 7 are also provided between the wall of this aperture and the supports 6 which communicate with a suitable air space 8 in the boiler 20 and open downward into the interior of the casing 2 and other air spaces therein as hereinafter described. It will also be noted that the vertical tubes 9 of the boiler, only three of which are illustrated, also open into the interior of this casing 2. It will also be understood that these tubes are adapted to be cleaned from the top and while the boiler 1 remains in position on the casing 2, a removable cover member 10 being provided for this purpose on the top of the boiler, while the products of combustion from these tubes 9 pass out through a suitable flue 11.

Referring next to the casing 2, it will be observed that the same herein includes generally horizontally disposed top and bottom members 35 12 and 13, herein in the form of castings, and an outer vertical sheet metal side member 14 standing between said members and herein also having an opening 15 at its front end to receive the slide 3, as hereinafter described. As shown, 40 the top member 12, in addition to the aperture 4 and parts 6 heretofore described, is herein also provided with a suitable series of air circulating openings 16 at the front thereof; while the bottom member 13 is also so spaced above the floor and provided with openings 17 and 18 under the openings 16 and 7, respectively, in the upper member 12, as to provide for free circulation of air. Here it will also be noted that transversely disposed partition members 19 divide the interior 45 of the casing 2 into front and rear portions 20 and 21. In the rear portion 21 a combustion chamber 22 is provided. As shown, an inner sheet metal lining member 23 provides the side and back walls of this chamber and the latter 50 has a front opening 24 therein. Attention here is

also directed to the fact that substantial air spacing, overlying the openings 18 and communicating with the openings 7, is thus provided between the casing member 14 and the member 23 forming the walls of the combustion chamber. It will also be noted that the front end of the member 23 is spaced inwardly and from the partition members 19, while one of the air inlets 18 is disposed beneath the space between the opening 24 and a like opening 24a between the partition members 19. As shown, upstanding flanges 25 and 26 spaced from one another longitudinally of the casing, of which the flange 26 is higher than the flange 25, are also provided on the bottom member 13 in front and rear of this opening 18, while corresponding depending flanges 27 and 28 are provided on the top member 12 to cooperate with the slide while maintaining air circulation, as hereinafter described. Also, it will be observed that stationary, ribbed, slide supporting and guiding portions 29 are provided on the member 13 in the bottom of the chamber 20 leading from the opening 15 centrally to the openings 24a, 24.

Cooperating with the boiler 1 and casing 2 is the improved slide mechanism, generally indicated at 3, and on the front end of which the burner is carried, the slide being freely movable between the positions shown in Figures 1 and 2. Herein this mechanism includes a slide member 30 in the form of a casting, and slidable along and over the portions 29 from the withdrawn position shown in Figure 1 to the operative position shown in Figure 2. This member 30 herein is also provided with depending vertical flanges 31 in its inner end slidable along the ribs of the portions 29 from the position shown in Figure 1, while the flanges are receivable through suitable slots 29a provided in the flanges 25 and 26 on the member 13 and shown in Figure 4, to the position shown in Figure 2. Herein, depending transverse longitudinally spaced flanges 32, 33 are also provided intermediate the ends of the slide 30, of which the flange 32 is the longer and adapted to engage the outer face of flange 25. Further, the flange 33 passes over the top of this flange 25 on the member 13 and engages flange 26 thereon. In front of these flanges, longitudinally extending flanges 34 are also provided, these flanges 34 corresponding to the flanges 31 and likewise being supported and guided by the portions 29. Depending feet 35 are also preferably provided on the outer ends of these flanges 34 to provide supports for the slide 30 in the withdrawn position thereof illustrated in Figures 1 and 3 when the inner end thereof is supported on the outer end of the member 13. Preferably vertical slots 36 are also provided in the outer end of the member 13 and in alignment with the slots 29a. Also, the slots 36 are of such depth as to receive the feet 35 and enable them to be disposed flush with the front of the member 13 when the slide is pushed in. While these feet 35 are herein formed integral with the cast slide 30, the same may be separately formed and attached thereto, and it will also be evident that, if desired, suitable rollers may be provided thereon to facilitate the movement of these feet over the floor as the slide is pulled out.

Referring more particularly to the burner mechanism carried on the slide 30, it will be observed that the burner mechanism proper, generally indicated at 37, is carried on the inner end of the slide above the front flanges 31, while 75

the fuel supplying mechanism and the controlling mechanism for the burner, generally indicated at 38, and the air supplying mechanism including the motor 39 and blower 40, are carried on the outer end portion of the slide. Herein, the burner 37 is also mounted on the front end of a longitudinally extending conduit 41 leading inward from the blower 40 and passing through a suitable aperture 42 above the flanges 32 and 33. Further, these flanges herein form depending parts of longitudinally spaced lower plates 43, 44, forming closures for the lower portion of the openings 24, 24a. Also, herein, upper longitudinally spaced plates 45, 46, forming upward extensions of these plates 43 and 44 closing the remainder of these openings 24, 24a, are suitably connected to the plates 43, 44 as by bolts 47. Of these upper plates 45 and 46, it will also be observed that the plate 45 passes beyond the lower end of the flange 27 on the upper casing member 12 and engages the flange 28 thereon, while the plate 46 is higher and engages the outer surface of the flange 27, all in such manner as to close the openings 24, 24a in the combustion chamber 22 when the burner 37 is in operative position therein. Further, it will be observed that a closure plate 48, suitably fixed to the outer end of the slide, closes the opening 15 in the casing 2, while a handle 49 is provided on the outside of this closure plate and near the bottom thereof and suitably connected to the end of the slide, in such manner as to enable the whole slide to be readily withdrawn. Moreover, it will be observed that a fuel pipe 50 is suitably separably connected as at 51 to the oil supply of the control mechanism, generally indicated at 38, by a suitable stationary connection, in such manner that fuel may be supplied as necessary from this control mechanism to the burner 37 through usual stationary connections. A connector plug 52 connected to the motor and other electrical connections of the device, is provided on the outer surface of the closure plate 48 so that a line conductor may be suitably connected thereto by a suitable plug 53.

In the use of my improved construction, it will be observed that the slide 30 and all the fuel and air supplying mechanism for the burner thereon forms a unit capable of being inserted bodily longitudinally in the casing 1 from the position shown in Figures 1, 3 and 4 to the position shown in Figure 2. Further, when the fuel and electrical connections are made to the closure plate 48, it will be evident that the burner mechanism is capable of operating in a normal manner in the combustion chamber 22. Note further that the latter has its openings 24, 24a closed by the plates 43, 44, 45 and 46, while a suitable air supply to the burner 37 is maintained by the blower 40 and air is admitted to the latter through the openings 16, 17. Attention further is directed to the air circulation and insulation provided by the passages between the members 14 and 23 and between the plates 43, 45, and 44, 46, which communicate with the openings 18 in slide 30 and member 13 and with the openings 7 in the top member 12. Thus, it is made possible to cut down objectionable radiation of heat from the combustion chamber by this air circulation leading up within the shell of the boiler. At the same time, the plates 43, 44, 45, 46 serve effectually to prevent overheating of the supply and control connections for the burner mechanism.

As a result of my improved construction, it

will further be observed that whenever it is desired to service the burner or clean the boiler tubes 9, it is possible to withdraw the burner 31 in such manner as to enable these tubes to be cleaned from the top, upon removal of the cover 10, and permit any material in the tubes to fall into the combustion chamber or a suitable receptacle therein, without fouling the burner 31. Further, if any need arises for repair of any of the mechanism on the slide 38, it is only necessary to withdraw the same to obtain access to any part thereon. Also, should the repair be of such nature as to be incapable of being made by a service man at the installation, the entire drawer may be replaced by another complete unit and the defective drawer shipped to the factory as necessary. These and other advantages of my improved construction will, however, be apparent to those skilled in the art.

While I have in this application specifically described one embodiment which my invention may assume in practice, it will be understood that the same is shown for purposes of illustration and that the invention may be modified and embodied in various other forms without departing from its spirit or the scope of the appended claims.

What I claim as new and desire to secure by Letters Patent is:

1. In combination, a generally horizontally disposed heater casing open at one end and having a partition between its ends defining a combustion chamber therein, and said casing providing a passage between said combustion chamber and said open end, oil burner mechanism including a support insertable in said casing through said open end and passage and also having a burner located in said combustion chamber when said support is so inserted and fuel supplying mechanism for said burner on said support in said passage between said burner and the open end of said casing, and a combustion chamber closure on said support between said burner and said supplying mechanism cooperating with said partition to isolate said combustion chamber from said passage.

2. In combination, a generally horizontally disposed heater casing open at one end and having a partition between its ends defining a combustion chamber therein, and said casing providing a passage between said combustion chamber and said open end, oil burner mechanism including a slide insertable in said casing through said open end and passage and having a burner located in said combustion chamber when said slide is so inserted and fuel supplying mechanism for said burner on said slide disposable in said passage means between said burner and the open end of said casing, and heat insulating means for said combustion chamber around the latter and including a combustion chamber closure on said slide between said burner and said supplying mechanism cooperating with said partition to isolate said combustion chamber from said passage.

3. In combination, a generally horizontally disposed heater casing open at one end and having a partition between its ends defining a combustion chamber therein, and said casing providing a passage between said combustion chamber and said open end, oil burner mechanism including a slide insertable in said casing through said open end and passage and having a burner located in said combustion chamber when said slide is so inserted and fuel supplying mechanism for

said burner on said slide between said burner and the open end of said casing, and upstanding inner and outer closure means carried at spaced points on said slide and cooperating respectively with said partition and the open end of said casing to form a closure for said combustion chamber and for said casing when said slide is inserted therein.

4. In combination, a generally horizontally disposed heater casing open at the front having a top opening in the rear end thereof adapted to communicate with a flue, a partition between the ends of said casing defining a combustion chamber beneath said top opening and also having a front opening, oil burner mechanism including a slide insertable in said casing through the open front thereof and having a burner thereon located in said combustion chamber when said slide is so inserted, and a combustion chamber closure carried by said slide between the ends thereof cooperating with said partition when said slide is inserted in said casing to close the open front of said combustion chamber.

5. In combination, a generally horizontally disposed casing having an opening at one end thereof, a flue, and a combustion chamber communicating with said flue comprising spaced inner and outer casing members, said inner casing member being spaced from said outer member to form an outer insulating chamber surrounding the combustion chamber and having a side entrance leading into the latter, an oil burner disposed in said combustion chamber, burner supporting slide means for enabling longitudinal insertion or withdrawal of said burner through said entrance, and a closure for said entrance movable with said burner and having spaced walls engaging the walls of said inner and outer casing members around said entrance to complete the double walled enclosure around said combustion chamber.

6. In combination, a generally horizontally disposed heater casing open at one end and having a partition between its ends defining a combustion chamber and having a boiler aperture in the top of said chamber, an angularly related boiler over said combustion chamber having tubes opening into the latter, oil burner mechanism in said casing having a burner in said combustion chamber and fuel supplying mechanism for said burner in the opposite end of said casing, slide mechanism carrying said burner mechanism and supplying mechanism and removable from said casing to remove said burner mechanism through said open end during cleaning of said boiler tubes, and combustion chamber closure forming means carried on said slide mechanism between said burner and supplying mechanisms cooperating with said partition for closing said combustion chamber when said slide mechanism is inserted in said casing.

7. An oil burner unit adapted to be horizontally inserted in and withdrawn from a casing comprising a horizontal slide, an oil burner on one end thereof, fuel supplying mechanism for said burner on the opposite end of said slide, an upstanding combustion chamber closure on said slide between said burner and said supplying mechanism, an upstanding casing closure on said slide on the opposite end of the latter from said burner, and supply connections on said second closure connected to said mechanism and connectable to a fuel supply line.

8. In combination, a heater casing having a combustion chamber in one end thereof, a boiler

over said combustion chamber having passage means opening into said casing around said combustion chamber, oil burner mechanism in said casing having a burner in said combustion chamber and supplying mechanism for said burner in the opposite end of said casing, and means for

5 maintaining air circulation around said chamber and between said burner and supplying mechanism and up through said passage means in said boiler.

WILLIAM A. PURTELL.
